PAGE 5

FIG. 5

FIG. 6

FIG. 1 is a right hand front perspective view of a combined microfilm viewer and reproducing machine accessory showing our new design;

FIG. 2 is a front elevational view thereof;

FIG. 3 is a right side elevational view thereof;

FIG. 4 is a left side elevational view thereof;

FIG. 5 is a top plan view thereof; and,

FIG. 6 is a rear elevational view thereof.

We claim:

The ornamental design for a combined microfilm viewer and reproducing machine accessory, as shown.
